(57) CLAIM

The ornamental design for a table, as shown and described.

DESCRIPTION

FIG. 1 is a perspective view of a table showing my new design;

FIG. 2 is a top view thereof;

FIG. 3 is a bottom view thereof;

FIG. 4 is a left side view thereof, the right side view being a mirror image;

FIG. 5 is a front view thereof; and,

FIG. 6 is a rear view thereof.

The broken lines are for environmental purposes only and form no part of the claimed design.

1 Claim, 4 Drawing Sheets

FIG. 2
